UNITED STATES PATENT OFFICE

2,647,481

FEED MECHANISM FOR SEWING MACHINES

Jean Court, Chatelaine-Geneva, Switzerland, assignor to Mefina S. A., Binningen, Switzerland, a corporation of Switzerland

Application July 10, 1951, Serial No. 235,963
In Switzerland July 17, 1950

2 Claims. (Cl. 112—210)

1

The present invention has for its subject an actuating mechanism for the feed dog of a sewing machine with free work-arm, in which the feed dog is carried by a support connected to an actuating member by means of two levers of which the first is rigid and rocks about a fixed vertical shaft, whilst the second, which is resilient, constitutes, with the first, a deformable parallelogram and rocks around a fixed horizontal axis.

In sewing machines with a free work-arm comprising an actuating mechanism for the feed dog of the type above referred to, the actuating member comprises a cam acting on the two levers at the same time. However, as is the case in the mechanism described in U. S. Patent No. 2,578,225 of December 11, 1951 to Casas-Robert et al., it is necessary that the parts of the said levers, adapted to follow the contour of the cam, are subjected to the action of springs which tend to hold the said parts constantly applied against the cam. But such mechanism is complicated and further, at a high speed of the sewing machine, it is possible, especially when the springs become weak, that shocks or at least vibrations are created in the said mechanism and are transmitted to the entire machine.

The mechanism forming the subject of the invention tends to remedy the said disadvantages. One feature of the invention is that the movement of oscillation of the rigid lever is transmitted thereto by the actuating member by means of a device for converting a movement of rotation into a reciprocating movement, acting at one end of a transverse lever pivoted at a point intermediate of its length to one end of the rigid lever, the other end of the transverse lever being hinged to one end of an arm of which the other end pivots at a point of the machine capable of being moved transversely to the pivotal axis, in such a manner as to allow of adjustment of the amplitude of movement of oscillation of the rigid lever and the reversal of the direction of advance of the feed dog.

One form of construction of the said mechanism is shown by way of example in the accompanying drawings, wherein:

Fig. 1 is a perspective view, and

Fig. 2 is a partial plan view.

Fig. 3 is a plan view of the mechanism in the lower arm of the sewing machine for actuating the feeder.

In this mechanism, the feed dog 1 is carried by a support 2 connected to an actuating member by means of two levers 3 and 4.

The lever 3 is rigid and oscillates about a sta-

2

tionary vertical axis 5, carried by the frame or base 30 while the lever 4 is resilient and oscillates about a stationary horizontal axis 6 also carried by the frame or base 30.

The lever 3 carries at one of its ends a pin or pivot 7, the ends of which slide vertically in bores in two limbs with which the support 2 is provided.

The actuating member is provided with a pinion 8 with a vertical axis, adapted to be driven in rotation by a tangential screw 29a, secured to a driving shaft 29 of the machine arranged longitudinally in the arm thereof and also serving to drive the shuttle.

The movement of oscillation of the rigid lever 3 is transmitted thereto from the actuating member 8 by means of a device for converting a movement of rotation into a reciprocating movement. This device is provided with a link 9 driven by an eccentric 10 secured to the pinion 8. The end of the link 9 is hinged to one of the ends of a transverse lever 11 pivoted to one end of the rigid lever 3. The other end of the transverse lever 11 is hinged to one end of an arm 12 of which the other end pivots on a pivot 13 of the machine capable of being moved transversely to itself.

For this purpose the pivot 13 is secured to the end of a lever arm 14 secured to a vertical shaft 15 turning in the framework of the machine. To the upper end of the said shaft 15 is secured a second lever arm 16 forming a handle projecting from the machine and enabling the pivot 13 to be moved in an arc of a circle.

A cam 17 is provided for controlling the movements of oscillation of the resilient lever 4. The cam 17 is cylindrical and circular and is secured to the pinion 8. It is provided with a cam surface on its bottom end face. The resilient lever 4 is formed by two main parts 18 and 19. The part 18 is a resilient blade and is secured by a strap 20 to the part 19 which is rigid. Said lever is extended by a part 21 which is adjustable relatively to the parts 18 and 19. In fact the part 21 is secured by a pin 22 and a screw 23 to the part 19. Said part 21, which is rigid, forms one end of the resilient lever 4 and the cam 17 acts thereon. The part 21 is guided in a slotted guide 27 surrounded by a coil spring 28 to keep the part 21 engaged with the cam surface. This structure is similar to that of the above mentioned Patent No. 2,578,225. The other end of the resilient lever 4 is connected to the support 2 by a pin 24 in such a manner as to transmit to the feed dog 1 its upward and downward movements.

As the cam 17 and the eccentric 10 are secured to the pinion 8, the movements of oscillation

3

about the pivot 6 of the lever 4 and the movements of oscillation about the pivot 5 of the lever 3, are synchronised.

It is also to be observed that the distance of the pivot 13 from the hinge pivot 25 of the arm 12 on the transverse lever 11 is the same as that separating the said pivot 25 from the pivotal axis 26 of the transverse lever 11 on the rigid lever 3.

The operation of the mechanism described above is as follows:

When the two pivots 13 and 26 are brought into coincidence with one another by means of the handle 16 and the pinion 8 is set in rotation, the cam 17 produces the upward and downward movements of the feed dog and the eccentric 10, by acting on the transverse lever 11 through the medium of the link 9, causes the latter to rock about its pivotal axis 26 without producing any movement of oscillation of the lever 3 and, consequently, the feed dog 1 is not subjected to any forward movement. When acting on the handle 16 the pivot 13 is moved either to one side or the other of the transverse lever 11, the movements of oscillation transmitted to the transverse lever 11 producing in turn movements of oscillation of the lever 3 about the pivot 5, thus producing a to-and-fro movement of the feed dog.

According to the position of the pivot 13 on one side or the other of the transverse lever 11, the feed dog 1 advances either in one direction or the other. For this reason it will thus be seen that the handle 16 allows, on the one hand, adjustment of the amplitude of oscillatory movement of the rigid lever 3 and, on the other hand, reversal of direction of advance of the feed dog 1.

From the foregoing description it will be seen that the movements, either in a vertical plane or in a horizontal plane, of the feed dog, are always synchronised, in view of the fact that they are controlled by a cam and an eccentric secured to the same pinion and that, further, the movements in a horizontal plane are not dependent on any spring.

The movements in a horizontal plane, either in one direction or the other, of the feed dog, are for this reason always controlled in a positive manner by the pinion 8.

In a modification, the pinion 8, instead of having a vertical axis, may turn about a horizontal axis. In this case, the cam 17 may be an ordinary cam. However, it is then necessary for the hinge of the link 9 on the transverse lever 11 to be of the ball type.

Further, the link 9 and eccentric 10 device may

4

be replaced by a link and crank device or by any other device for converting a rotary movement into a to-and-fro movement.

I claim:

- 5 1. An actuating mechanism for the feeding device of a sewing machine comprising a driving element, a rigid lever mounted for rocking movement about a fixed vertical axis, an eccentric mounted for rotation about a vertical axis and driven by said driving element, a transverse lever pivotally connected intermediate its ends to one end of the rigid lever for pivotal movement relative thereto about a vertical axis, a connecting rod connecting the eccentric to one end of the transverse lever for imparting rocking movement to said transverse lever, an arm mounted at one end for adjustment about a fixed vertical axis, a link connecting the other end of the arm to the other end of the transverse lever, means for adjusting the arm about said fixed vertical axis to vary the angular relation between said link and transverse lever to vary the direction and amplitude of rocking movement of the rigid lever imparted thereto by rocking movement of the transverse lever, means transmitting horizontal oscillating movement from the other end of the rigid lever to said feeding device, a second lever mounted for rocking movement about a fixed horizontal axis, said second lever having an input arm and an output arm, means connecting the output arm of the second lever to the input arm thereof to render the output arm rigid with the input arm in a vertical plane but to enable the output arm to oscillate in a horizontal plane relative to the input arm, means for transmitting oscillating movement in a vertical plane to the end of the input arm, and means for transmitting vertical oscillating movement from the end of the output arm to said feeding device.
- 10 2. A mechanism according to claim 1 in which the means for transmitting oscillating movement to the input arm of the second lever comprises a cam carried by the eccentric.
